BOWLING BALL FINGER HOLE SIZING AND POSITIONING GUIDE

Wilson G. Taylor, 2901 West Valley,
Alhambra, Calif. 91803

Filed Oct. 3, 1972, Ser. No. 294,644

Term of patent 7 years

Int. Cl. D10—04

U.S. Cl. D10—70

Fig. 1

Fig. 2

Fig. 3

Fig. 4

FIG. 1 is a top perspective view of a bowling ball finger hole sizing and positioning guide showing my new design; FIG. 2 is a bottom plan view thereof;

FIG. 3 is a side elevational view of FIG. 2;

FIG. 4 is a front edge elevational view of FIG. 2.

I claim:

The ornamental design for a bowling ball finger hole sizing and positioning guide, as shown.
